FIG.1

FIG.2

1

2,832,986

CONVERTIBLE AIR SUPPORTED SUCTION CLEANER

Werner G. Seck, Canton, Ohio, assignor to The Hoover Company, North Canton, Ohio, a corporation of Ohio

Application April 6, 1956, Serial No. 576,734

5 Claims. (Cl. 15—327)

The present invention relates to suction cleaners and more particularly to suction cleaners of the so called canister type by which cleaning is done by means of a cleaning tool attached to a motor-fan-filter unit by means of a flexible suction hose.

Such cleaners may be towed about by means of pulling on the suction hose. The present invention relates to that type of cleaner in which the towing operation is facilitated by supporting the motor-fan-filter unit on a cushion of air as exemplified by a co-pending application by Curtis C. Coons and John C. Montgomery, Serial No. 418,512, filed March 25, 1954, Patent No. 2,780,826, dated February 12, 1957 and a co-pending application by Louis K. Acheson, Serial No. 429,940, filed May 14, 1954, now Patent No. 2,751,038, dated June 9, 1956.

The present invention is an improvement over the above mentioned applications and relates to an arrangement whereby the cleaner may be selectively used as an air supported cleaner or as an ordinary base supported cleaner in which the air supporting feature is not used.

In cleaners of the air supported type, the exhaust air flows into a plenum chamber formed between the base of the cleaner and the surface upon which the cleaner rests. The plenum chamber is formed by an annular supporting rim closing an annular air space into which the exhaust air discharges. An air pressure is built up within the plenum chamber sufficient to support the cleaner on a cushion of air, the rim being raised sufficiently to permit the escape of exhaust air between its lower edge and the surface upon which the cleaner rests. A number of protuberances projecting slightly below the supporting rim may be provided to prevent the cleaner from chattering and to stabilize it when it is supported on a bare floor.

According to the present invention an auxiliary air outlet is provided which is normally closed by a removable sleeve like member. When the sleeve is removed the air flows through an annular diffusing opening between the base of the cleaner and the main body of the cleaner.

Other objects and advantages of the present invention will become apparent as the description proceeds when taken in connection with the accompanying drawings in which:

Fig. 1 is a side view of a cleaner according to the present invention partly broken away to show the details of construction and showing the cleaner air supported and,

Fig. 2 is a segmental sectional view of the cleaner of Fig. 1 showing the path of exhaust air flow when the cleaner is not air supported.

The cleaner of the present invention is generally represented by the reference numeral 10 and comprises upper and lower casing halves 11 and 12 respectively hinged together at 13 and held closed by a suitable latch 14.

The upper casing encases a filter 15 and is formed with a suction inlet fitting 16 to which one end of the flexible hose is adapted to be attached, the other end of the hose being connected to a suitable cleaning tool.

The upper and lower casing halves 11 and 12 are sepa-

2

rated by a bulkhead (not shown) provided with an opening leading to the suction inlet of a motor-fan unit 17 suitably supported within the lower casing half 12.

The motor windings may be connected to the usual household electrical outlet by an electric cord 18 and is adapted to be controlled by an electric switch 19.

The cleaner body 10 is pivoted at 20 to a base generally indicated by the reference numeral 21 and is normally held in its downward position by a latch 22. The lower casing half 12 is provided with blower fitting 23 whereby the body 10 may be pivoted upwardly and the flexible hose attached to the fitting 23 for blowing purposes.

The base 21 consists of an annular plate 25 having a downwardly extending annular rim 26 provided with a plurality of downwardly extending protuberances 29 peripherally spaced about the rim 26 and extending downwardly from the lower face of the rim 26 a few thousandths of an inch for a purpose which will later appear. For one type of cleaner the protuberances 29 may be from 0.020 to 0.025 inch in downward extent below the rim 26.

The space between the plate 25 and the lower edge of rim 26 forms a plenum chamber 27 into which exhaust air is discharged through an opening 28 in plate 25 immediately below the blower fitting 23. A ring like member 30 normally seats about the opening 28 at its lower edge and makes sealing engagement with the blower fitting 23 when the body 10 is latched to the base 21. The ring 30 is made of plastic material and is held in position by an integral rivet 31 extending through a small opening 32 in the plate 25 to one side of the opening 28.

The upper part of the base 21 comprising an annular plate 33 having a plurality of openings 34 about its periphery and positioned outwardly of the lower casing half 12. The space between a plate 25 and the lower casing half 12 enclosed by the annulus 33 forms a diffusing chamber under certain conditions as will later appear.

Operation

40 A hose having a suitable cleaning tool attached to its free end is attached to the suction fitting 16 and the motor energized by operation of the switch 19. Dirt laden air will be drawn inwardly through the hose and fitting 16 and into the filter 15 where the dirt will be separated from the moving air stream.

The cleaned air will pass through the bulkhead into the suction side of the fan and be discharged through the motor casing into the interior of the lower casing half 12. 50 The exhaust air under pressure will pass through the blower fitting 23, through the ring 30 and through the opening 28 in plate 25 into the plenum chamber 27 where a pressure will be built up sufficient to support the weight of the cleaner 10 on a cushion of air, the air escaping from beneath the lower edge of rim 26 to maintain the requisite pressure in the plenum chamber 27.

The protuberances 29 are not absolutely essential but prevent the cleaner from chattering when it is supported on the air cushion, more particularly the protuberances 60 29 actually prevent the cleaner from beginning to chatter.

When it is desired to use the cleaner 10 without the use of the air lift feature, the latch 22 is released and the cleaner body pivoted upwardly about the pivot 20 which removes the fitting 23 from contact with the ring 30 permitting the latter to be easily removed. The body 10 is then returned to its normal position and used in the normal manner.

The removal of the ring 30 provides for the free flow of air through the diffuser and openings 34. While that air flow passage is somewhat restricted and air flow into the plenum chamber 27 is permitted the back pressure in that chamber will not be sufficient to support the cleaner

10 and it may be used in the usual manner of using canister type cleaners.

In either case the body 10 may be tilted upwardly and a hose fitting inserted in the blower fitting 23 for blowing operations.

From the foregoing it can be seen that the present invention provides the simple arrangement by which a canister cleaner of the air supported type may be easily converted to an ordinary canister cleaner.

While I have shown and described but a single embodiment of my invention it is to be understood that that embodiment is to be taken as illustrative only and not in a limiting sense. I do not wish to be limited to the specific structure shown and described but wish to include all equivalent variations thereof except as limited by the scope of the claims.

I claim:

1. A suction cleaner comprising, a body having a suction inlet and an exhaust outlet, a suction creating unit within said body for drawing air into the suction inlet and for exhausting said air through said outlet, a supporting base for said body, a plenum chamber formed in said base and exposed over a substantial area to the surface upon which said body rests, a supporting rim surrounding said area, means including a separable member for leading exhaust air from said exhaust outlet to said plenum chamber whereby an air pressure is formed therein sufficient to carry the weight of the cleaner and excess air is diffused from beneath the bottom edge of said rim, a secondary air passage leading from said ex-

10 haust outlet direct to atmosphere, said secondary air passage being normally closed by said separable member whereby upon its removal a free path of air flow to atmosphere is provided for air exhausted by said suction creating unit.

5 2. A suction cleaner according to claim 1 in which said removable member is in the form of a ring lying between said exhaust outlet and a port leading to said plenum chamber and normally occupying the space between said body and base.

3. A suction cleaner according to claim 2 in which said body is pivoted to said base and said ring is accessible for removal when said body is pivoted upwardly relative to said base.

15 4. A suction cleaner according to claim 3 in which said ring like member is detachably secured to said base adjacent the port leading to said plenum chamber.

20 5. A suction cleaner according to claim 1 in which said secondary air passage is in the form of an annular space between said body and base communicating with atmosphere and acting as an air diffuser.
